UNITED STATES PATENT OFFICE.

LEO H. BOOCH, OF ST. LOUIS, MISSOURI, ASSIGNOR TO BRIDGE & BEACH MFG. CO., OF ST. LOUIS, MISSOURI, A CORPORATION OF MISSOURI.

DESIGN FOR A STOVE.

Application filed November 7, 1923. Serial No. 7,704. Term of patent 14 years.

To all whom it may concern:

Be it known that I, LEO H. BOOCH, a citizen of the United States, residing at St. Louis, Missouri, have invented a certain new, original, and ornamental Design for a Stove, of which the following is a specification, reference being had to the accompanying drawing, forming part thereof.

The figure is a perspective view of my new design.

I claim:

The ornamental design for a stove, as shown.

LEO H. BOOCH.
